His Attorney.

UNITED STATES PATENT OFFICE.

JAMES WILKINSON, OF PITTSFIELD, MASSACHUSETTS, ASSIGNOR TO GENERAL ELECTRIC COMPANY, A CORPORATION OF NEW YORK.

LEAD-BUSHING.

1,304,230.

Specification of Letters Patent. Patented May 20, 1919.

Application filed October 7, 1918. Serial No. 124,434.

To all whom it may concern:

Be it known that I, JAMES WILKINSON, a citizen of the United States, residing at Pittsfield, in the county of Berkshire, State 5 of Massachusetts, have invented certain new and useful Improvements in Lead-Bushings, of which the following is a specification.

My invention relates to lead bushings, particularly to those of the oil or compound 10 filled type adapted for insulating high tension leads where they pass through the walls of oil-filled tanks for electrical apparatus such as transformers and oil switches.

Heretofore, when bushings of the oil filled 15 type have arced or become damaged in such a way that they must be removed, considerable inconvenience has been experienced because the whole bushing must be removed, involving the labor of highly skilled work- 20 men where soldered joints and connections have been used for connecting the leads.

By the use of my improved bushing, a great part of the inconvenience and expense is avoided, since I preferably use only 25 clamped joints which may readily be opened by unskilled workmen for removing the damaged portion of the bushing independently of the other portions.

A further advantage of my invention re- 30 sults from the oil-tight character of the joints of the bushing. The parts of the bushing, or parts of the bushing and the tank or other carrying member for the bushing wall, are directly clamped together, each 35 joint being provided with its own clamping devices. It has been found that bushings of this character can be made very nearly absolutely oil-tight, considerably more so in fact than the bushings of the type long used but 40 employing a very simple clamping device for each bushing.

For a detailed understanding of my in- 45 vention, reference may be had to the accom- 50 panying drawing, in which Figure 1 illus- 55 trates a bushing constructed in accordance with my invention, partly shown in section and partly in elevation; Fig. 2 is a frag- 60 mentary section through a bushing embody- 65 ing a modified form of my invention.

Referring particularly to Fig. 1 of the 70 drawing, 5 denotes the casing wall of the electrical apparatus which contains a body of oil 6 or other carrying member for the bushing. The wall 5 has an opening 7 75 which is covered by inner and outer insu-

lator cones 8 and 9. These insulator cones may be made of any tough or infusible material, preferably a material which is capable of being molded under high temperature and pressure, such as, for example, "bakelite." 60

The insulators 8 and 9 are provided with flanged base portions 10 and 11, respectively, which are ground to fit tightly over the opening 7 in the casing wall 5.

In order to secure the insulator cones to 65 the casing 5 in a manner so that they can be readily removed, and so that the joints between the cones and the casing may be strictly oil-tight, I provide clamping rings 70 12 and 13 which fit down snugly over the flanged bases 10 and 11 and are each held in place by a series of bolts 14 secured in the casing wall 5.

In order to rigidly secure these bolts 14 in 75 the casing wall 5, I make them in a special form, threaded at both ends with a squared central portion 15 which is adapted to be brought up snugly against the casing wall by nut 16 and lock nut 17. The nuts 16 and 18, together with the squared portion 15, 80 make an oil-tight joint where the bolt 14 passes through the casing wall 5. The nuts 18 at each end of the bolts 14 engage with clamping rings 12 and 13 to secure them in place. 85

In order to avoid the turning of a bolt 14 after it is once in place, and thereby preventing the working loose of nuts 18, I provide a squared recess 19 in the under face of clamping ring 13 to engage with the squared 90 portion 15 of bolt 14. This affords a convenient and effectual means for preventing any tendency of the bolts 14 to turn or let the clamping rings become loose after the nuts 18 have once been driven into place. 95

In order to provide an oil-tight joint where the conducting lead 20 passes through the insulating cone 9, I form the lead 20 with an enlarged shoulder 21 for engaging with the inner surface of the cone 9, while 100 over the outer end of the lead I fit the cap 22. The cap and shoulder are brought snugly up against the cone 9 by means of nuts 23, the cone being ground so as to make a tight joint. 105

It is, of course, obvious to those skilled in the art that the insulating cones need not be ground in order to make an oil-tight joint where they fit over the opening in the casing wall 5 or where the conducting lead passes 110

through them. Any convenient packing may be used instead, such as a gasket 24, which I have shown in Fig. 2 as a modified form of my invention.

5 In order that the lead bushing may be always filled with oil, I provide the inner cone 8 with perforations 25 so disposed as to trap no air therein.

When it is desired to remove either the 10 inner or the outer cone, the oil level is first lowered and then the respective clamping ring is removed. This permits the removal of either cone without disturbing the other.

While I have described a specific lead 15 bushing embodying my invention, I would have it understood that my invention is not limited to the exact details which I have disclosed, except as defined by the claims hereto annexed.

20 What I claim as new and desire to secure by Letters Patent of the United States, is:

1. The combination with a casing wall 25 having an opening therein, of a lead bushing consisting of inner and outer insulating members provided with flanged portions and clamping members for independently securing each insulating member over the opening in the casing wall.

2. The combination with a casing wall 30 having an opening therein, of a lead bushing consisting of inner and outer conical members provided with flanged portions, clamping members for independently securing the conical members over the opening in 35 the casing wall and a conductor having clamping means for tightly securing the same in one of said conical members.

3. The combination with the wall of an oil filled casing provided with an opening

therein, of conical insulating members provided with flanged portions snugly fitting over said opening, clamping members engaging said flanged portions and a common securing means for said clamping members.

4. The combination with a perforated 45 wall of an oil containing casing, of insulating members provided with flanged portions, clamping members engaging said flanged portions, and double ended bolts passing snugly through the casing wall 50 whereby said insulating members are snugly and independently clamped over the perforations in the casing wall.

5. The combination with a perforated wall 55 of an oil containing casing, of inner and outer insulating members provided with flanges fitting over the perforations, said inner members being perforated so as to form with said outer member an oil filled bushing, annular clamping members engaging said flanges, double ended bolts each having a squared central portion and lock nuts for snugly passing said bolts through the casing wall and adapted to independently secure said clamping members, one of 65 said clamping members being provided with recessed portions for engaging the squared central portions of said bolts.

6. A lead bushing comprising the combination with two insulating members adapted to be filled with oil, of independently removable clamping members surrounding and engaging their respective insulating members, and common securing means therefor.

In witness whereof, I have hereunto set my hand this third day of October 1916.

JAMES WILKINSON.
